SCAVENGING OF THE CYLINDERS OF TWO-STROKE-CYCLE INTERNAL COMBUSTION ENGINES

William Cull, Shipley, England, assignor to Scott Motors (Saltaire) Limited, Shipley, England

Application July 12, 1939, Serial No. 284,060
In Great Britain February 23, 1938

4 Claims. (Cl. 123—65)

This invention relates to two-stroke-cycle internal combustion engines of the kind wherein a conical topped piston controls exhaust ports and transfer ports for combustible mixture compressed in the crank-case, and the passages behind the transfer ports are so disposed that the entering streams of gases are directed tangentially or radially with respect to the cylinder bore and transversely or with slight or steep upward inclination with respect to the cylinder axis.

The chief object of the present invention is to provide a new or improved construction of the cylinder of this kind of two-stroke-cycle engine wherein more accurate control of the gases during the transfer and exhaust periods is obtained so as to ensure more complete scavenging of the exhaust gases, and in consequence increased engine efficiency.

In two-stroke-cycle oil engines it has been proposed to employ a cylinder having three scavenging air ports on one side with exhaust ports on the opposite side, the outer two ports directing scavenging air in streams up the admission side of the cylinder to the combustion end of the latter, also, if desired, being deflected towards the cylinder wall, and the centre air port serving to direct scavenging air across the cylinder to the exhaust so as to clear the area near the piston end. It has also been proposed to provide a two stroke internal combustion engine with two scavenging ports arranged one on each side of the exhaust ports in such a manner that the issuing streams of scavenging air are directed to the cylinder wall opposite to the exhaust ports, the scavenging channels being inclined to a plane at right angles to the cylinder axis and the ports as seen in plan being directed to a point outside the cylinder opposite to the exhaust ports.

According to the invention only three transfer ports are provided, one transfer port is diametrically opposite to the exhaust port or ports and the other two transfer ports are disposed symmetrically one on each side of the cylinder relative to the first port and are provided with leads so that they are opened progressively by the movement of the piston, the angle which the passages behind the two further transfer ports make with the cylinder bore is such, that when seen in section transverse to the cylinder axis the lines of the side walls, when continued across the cylinder bore, strike the cylinder wall in points coincident with the side walls of the first mentioned transfer port.

In order that the invention may be clearly understood and readily carried into effect, the same will now be more fully described with reference to and by the aid of the accompanying drawings, wherein:

Figure 1 is a part sectional elevation of a cylinder of a two-stroke-cycle internal combustion engine.

Figure 2 is a sectional plan view taken along the line A—A of Figure 1, but with the piston removed for the sake of clearness.

Figure 3 is a part sectional elevation taken at right angles to Figure 1.

Figure 4 is a sectional plan view taken along the line B—B of Figure 3 but with the piston removed for the sake of clearness.

Referring to the drawings, the engine comprises a symmetrical piston 1 having a substantially conical crown 2 and working in a cylinder 3, the bore of which is provided with an exhaust port 4 leading therefrom and embracing up to approximately $\frac{1}{3}$ of the circumference of the cylinder bore. Diametrically opposite to the exhaust port 4 is a transfer port 5 supplied by a transfer passage 5' leading from the crank case 6 to which the gases are supplied by an inlet port 6', and two further transfer ports 7 are disposed equally on either side of the cylinder 3 relatively to the first or central transfer port 5. Transfer passages 7', one of which is shown in dotted lines in Figure 1, leads to each of the ports 7. The angle which the passages behind the two further transfer ports make with the cylinder bore is such that when seen in section transverse to the cylinder axis, the lines of the side walls, when continued across the cylinder bore, strike the cylinder wall in points coincident with the side walls of the first-mentioned transfer port 5 (see Figure 4).

In addition the passages behind the two further transfer ports 7 are also inclined upwardly and this upward direction is at approximately the same angle as the conical piston crown 2. In a preferred construction, this angle may be about 30° from the horizontal plane, which is at right angles to the vertical axis of the cylinder.

The two further or tangential transfer ports 7 are provided with transverse upwardly inclined openings or leads as at 8 so that they are opened progressively by the movement of the piston 1, the opening commencing at the exhaust port side. In this connection if desired, instead of leads being afforded by the tangential ports 7 such leads may be formed by correspondingly shaping the piston 1 so that the tangential ports 7 will open progressively commencing at the exhaust port side. The first transfer port 5 diametrically opposite the exhaust port 4 has no tangential control of the gases but the passage behind this port enters the cylinder at a greater angle than that which the passages behind the tangential ports 7 make with the horizontal plane which is at right angles to the vertical axis of the cylinder. In the preferred construction the angle which the passage behind the first transfer port 5 makes with the cylinder 1 would lie approximately between 57° and 63° to the said horizontal plane.

Thus it will be seen that as the piston moves from its upper compression stroke, as shown in dotted lines in Figure 1, downwardly in its working stroke, it uncovers the leads or openings 8 gradually. This is clearly illustrated in Figure 1, wherein the lead 8 commences to open when the piston uncovers the top righthand corner thereof, and as the piston descends the effective width of the opening increases until the piston uncovers 10 the top lefthand corner, and upon further downward movement the opening will remain constant.

Owing to the leads or openings 8 given to the two tangential transfer ports, the two streams of gases emitted therefrom cross the piston top 15 tangentially and unite as they commence to flow upwardly to the cylinder head 9 and behind the apex of the piston crown 2 towards the first port 5, whereupon said first port 5 opens and the united streams of gases are given an additional 20 velocity by the gas issuing from the first port 5 just at a time when the initial velocity of said streams is falling, so that the gases are carried over the piston crown to the exhaust port side. In this connection the gases entering through the 25 first port 5 pass through a Venturi throat 10 formed by restricting the area of the passage behind the said port 5 at a point immediately in advance of its opening into the cylinder 1.

Thus it will be seen that by giving the gases 30 which are delivered by the tangential ports an additional velocity in an upward direction, more effective scavenging of the spent or exhaust gases is ensured with consequently increased engine efficiency.

35 I claim:

1. A combustion engine of the class described including a cylinder, a reciprocating piston mounted in the cylinder, said piston having a conical crown, an exhaust port leading from the 40 cylinder, three transfer ports communicating with the cylinder, said ports being controlled by the movement of said piston, said cylinder having three spaced vertically disposed transfer passages, each passage being inclined upwardly and communicating with one of the transfer points, one of said transfer ports being disposed diametrically opposite to the exhaust port and constituting a central transfer port, the two other ports forming tangential ports disposed one 45 on each side of the central transfer port, means for progressively opening the tangential transfer ports upon the movement of the piston, and said tangential transfer ports facing the central transfer port so that the issuing gas streams are projected across the cylinder to impinge upon the stream entering the cylinder from the central transfer port at approximately the same angle as the conical piston crown.

2. A two-stroke-cycle combustion engine of the 60 class described including a cylinder, a reciprocating piston mounted in the cylinder, said piston having a conical crown, an exhaust port leading from the cylinder, three transfer ports communicating with the cylinder, said ports being controlled by the movement of said piston, said cylinder having three spaced vertically disposed transfer passages, each passage being inclined upwardly and communicating with one of the transfer ports, one of said transfer ports being disposed 65 diametrically opposite to the exhaust port and constituting a central transfer port, the two other ports forming tangential ports disposed one on each side of the central transfer port, the two

tangential transfer ports having upwardly transverse inclined openings communicating with the cylinder so that the tangential ports are progressively opened by the movement of the piston, and said tangential transfer ports facing the central transfer port so that the issuing gas streams are projected across the cylinder to impinge upon the stream entering the cylinder from the central transfer port at approximately the same angle as the conical piston crown.

3. A two-stroke-cycle combustion engine of the class described including a cylinder, a reciprocating piston mounted in the cylinder, said piston having a conical crown, an exhaust port leading from the cylinder, three transfer ports communicating with the cylinder, said ports being controlled by the movement of said piston, said cylinder having three spaced vertically disposed transfer passages, each passage being inclined upwardly and communicating with one of the transfer ports, one of said transfer ports being disposed diametrically opposite to the exhaust port and constituting a central transfer port, the two other ports forming tangential ports disposed one on each side of the central transfer port, the two tangential transfer ports having upwardly transverse inclined openings communicating with the cylinder so that these ports are progressively opened, by the movement of the piston, said tangential transfer ports facing the central transfer port so that the issuing gas streams are projected across the cylinder to impinge upon the stream entering the cylinder from the central transfer port at approximately the same angle as the conical piston crown, and said central transfer port having a Venturi throat formed by restricting the area of said passage at a point immediately in advance of its opening into the cylinder.

4. A two-stroke-cycle combustion engine of the class described including a cylinder, a reciprocating piston mounted in the cylinder, said piston having a conical crown, an exhaust port leading from the cylinder, three transfer ports communicating with the cylinder, said ports being controlled by the movement of said piston, said cylinder having three spaced vertically disposed transfer passages, each passage being inclined upwardly and communicating with one of the transfer ports, one of said transfer ports being disposed diametrically opposite to the exhaust port and constituting a central transfer port, the two other ports forming tangential ports disposed one on each side of the central transfer port, the two tangential transfer ports having upwardly transverse inclined openings communicating with the cylinder so that these ports are progressively opened, by the movement of the piston, said tangential ports facing the central port, whereby the streams of gases emitted from the tangential ports cross the piston top tangentially and unite as they commence to flow upwardly to the cylinder head and when said central port opens the united streams of gases are given an additional velocity by the gas issuing from the central port just at a time when the initial velocity of said streams is falling, the inclined passage of the central port entering the cylinder at approximately twice the angle which the passages communicating the tangential ports make with a horizontal plane disposed at right angles to the vertical axis of the cylinder.

WILLIAM CULL.
